TRACK RAIL FOR CURTAINS AND THE LIKE

Jean-Pierre Duperrex, 44 Rue des Moulins,
Yverdon, Switzerland

Filed Feb. 5, 1973, Ser. No. 329,317

Claims priority, application Switzerland Aug. 4, 1972

Term of patent 14 years

Int. Cl. D8—99

U.S. Cl. D8—208

FIG. 2

FIG. 1 is a fragmentary perspective view of a portion of my novel track rail for curtains and the like, it being understood that the remaining portion would extend in the same configuration as the portion shown, all surfaces being unornamented; and

FIG. 2 is an enlarged end view thereof.

I claim:

The ornamental design for a track rail for curtains and the like, as shown and described.
